UNITED STATES PATENT OFFICE

113,892

DESIGN FOR A MASK FOR A TYPEWRITING MACHINE

Bernard J. Dowd and Henry J. Hart, West Hartford, Conn., assignors to Royal Typewriter Company, Inc., New York, N. Y., a corporation of New York

Application September 30, 1938, Serial No. 80,157

Term of patent 14 years

To all whom it may concern:

Be it known that we, Bernard J. Dowd and Henry J. Hart, both citizens of the United States, residing at West Hartford, in the county of Hartford and State of Connecticut, have invented a new, original, and ornamental Design for a Mask for a Typewriting Machine, of which the following is a specification, reference being had to the accompanying drawings, forming part thereof.

We claim:

The ornamental design for a mask for a typewriting machine, as shown.

BERNARD J. DOWD.
HENRY J. HART.
